UNITED STATES PATENT OFFICE.

FREDERICK G. ROBINS, OF MONTREAL, QUEBEC, CANADA.

WINDING MACHINE.

Application filed November 8, 1926. Serial No. 147,056.

The present invention pertains to a novel winding machine designed particularly for winding ribbon-like material upon a card in such a manner that the material is laid in contiguous windings across the card.

In an operation of this character the material is necessarily moved relatively across the card and held stationary in a given position until one winding is completed. Then 10 the card or the guide, in the present case the guide, is moved to the next position to permit the laying of the next adjacent winding. It will be evident that two successive windings must be made in each final 15 position before the guide is permitted to proceed in its reverse direction, otherwise the end windings will be only half as thick as the intermediate windings.

The accomplishment of such a function is 20 the object of the present invention. The machine comprises essentially a frame in which is mounted a rotatable card holder and a slidable guide for the material to be wound. The device for turning the holder 25 is geared to a mechanism for driving the guide in such a manner that the latter is shifted in a step-by-step movement. Preferably, a Geneva movement is interposed in the gearing for this purpose. The particular 30 guide driving device consists of a drum actuated by the above mentioned gearing and having on its surface a track which has a nut connection with the guide. The construction of this track is such as to advance 35 the guide one step for each rotation of the holder and to permit the guide to remain in its end positions during two consecutive turns of the holder.

The invention is fully disclosed in the 40 following description and in the accompanying drawings in which;

Figure 1 is a plan view of the machine;

Figure 2 is a fragmentary plan view thereof showing a card inserted therein and prior 45 to being wound;

Figure 3 is a side elevation;

Figure 4 is a fragmentary plan view showing a card inserted in the machine and partly wound;

Figure 5 is a front elevation;

Figure 6 is a section on the line 6—6 of

Figure 4;

Figure 7 is a plan view of the drum;

Figure 8 is a fragmentary side elevation of the frame; and

Figure 9 is a section on the line 9—9 of Figure 6.

Reference to these views will now be made by use of like characters which are employed to designate corresponding parts throughout.

The frame of the machine comprises a base 1 on which are erected side members 2 and 2' each of which includes a forward leg 4 and a taller rear leg 5.

The rear legs 5 are formed at their upper ends with bearings 6, and the bearing at the side 2 receives a stub shaft 3. The inner end of the shaft carries a large wheel 6' to which is secured a straight grooved jaw 7. The other end of the shaft carries a crank 8 secured thereto by a pin 9. The other bearing 6 receives a slidable and rotatable stub shaft 10 having at its inner end a grooved jaw 11 similar to the member 7, but shorter, and at its outer end a knob 12. Between the bearing and the jaw 11, the member 10 is surrounded by a coil spring 13 which tends to move the jaw 11 towards the jaw 7, the movement in this direction being limited by the engagement of the knob 12 with the other side of the bearing.

The forward legs 4 are provided with intermediate bearings 14 which support a horizontal shaft 15. On this shaft is mounted a drum 16, the detailed construction and operation of which are described below. One end of the shaft 15 carries a gear 17 as clearly shown in Figures 1, 3 and 5.

The frame side 2 is formed at an intermediate point with a bearing 18 in which is mounted another stub shaft 19. At the outer side of the frame, this shaft carries a pinion 20 held by a nut 22, and at the other side a Geneva spider 23. Adjacent the wheel 6', the stub shaft 3 carries a smaller wheel 24 to which is attached a pin 25 adapted to enter the slots 26 of the Geneva spider 23. At both sides of the pin 25, the wheel 24 is reduced in thickness as at 27 to permit penetration of the points of the spider 23 into the circle defined by the wheel 24.

The frame 2 is formed intermediate its legs with a web 20^a in which is drilled a series of bearing apertures 20^b. Any one of these apertures is adapted to receive a pin 20^c to which is secured by means of a nut

20^a an intermediate gear 20^e meshing with the gear 17 and pinion 20. By means of this train of gearing, the pinion 20 transmits movement to the drum shaft 15.

5 The upper end of each leg 4 is formed with a pair of bosses 28 designed to receive a pair of parallel guide rods 29. These rods are bridged by a block 30 slidable thereon, and a pair of angle pieces 31 are mounted 10 on the top of the block to form a space lying transversely thereof. Each member 31 has its lower or horizontal leg formed with a slot 32. By means of bolts 33 passed through the slots and into the block 30, the 15 space 34 between the angle members may be regulated in its width.

The surface of the drum 16 carries two spiral track segments 35, each extending longitudinally of the drum and covering substantially half of the circumference thereof. 20 These segments may be described as being directed oppositely to each other, rather than in parallel relation, so that the ends of one segment lie adjacent the ends of the other. 25 These adjacent ends are joined, and the track is made continuous or endless, by means of curved segments 36 of less extent with reference to the circumference of the drum.

30 Into the base of the guide block 30 is loosely threaded a screw 37 carrying a nut 38 at its lower end. A washer 39 is interposed between the nut and the block. The loose mounting of the nut permits the latter to 35 turn on the curves of the track, and the ends of the slot 40 are furthermore flared as at 41 to avoid binding of the nut during such turning movements.

In the use of the device the jaw 11 is 40 retracted by means of the knob 12 in order to permit insertion of a card 42 on which the material is to be wound. When the knob 12 is released, the card is clamped between the jaws 7 and 11 by means of the spring 45 12. The material to be wound, which is of a ribbon-like nature, is held in any suitable manner as on a ball or roll in front of the drum 16. One end of the material is passed 50 through the space 34 in the guide and is attached to the card by means of a flat spring member 43 carried by one end of the jaw 7. The card is rotated by turning the crank 8, whereupon the material is wound upon the card.

55 The Geneva movement already described effects intermittent rotation of the pinion 20, and this movement is transmitted to the drum 16, resulting in a step-by-step movement of the guide along the rods 29. The 60 gears and the track are so calculated that the guide will remain stationary for the greater part of each turn of the crank 8, during which period the material is wound once on the card and will then be moved

rapidly to the next position by the Geneva 65 movement. Consequently the material is laid on the card in contiguous windings 44 as shown in Figure 4.

It has been stated that two consecutive turns are required on each of the end windings 45 before the guide is reversed in its direction—one turn for the direction completed by the guide at the end of the card and one turn immediately after reversal. This function is accomplished by the peculiar formation of the end track segments 36 as already described in detail. By means of these segments, the guide after completing each final winding is rapidly thrown beyond the final position and returned to the 80 same point so that another winding may be applied immediately over the end winding already laid. This operation occurs at both ends of the drum since they are identical in construction.

It will be evident that the ends of the track, or the entire configuration thereof, may possibly be designed in a different manner to accomplish the same function of the machine, i. e., to retain the guide 30—34 90 in the end positions with respect to the drum during two turns of the crank 8 for the purpose discussed above in detail. In the present instance, however, this function is accomplished apparently by constructing the 95 end segments 36 to have a considerably shorter radius of curvature than the main segments 35, whereby the movement of the guide is more rapid on the end segments than elsewhere.

The machine is furthermore constructed to provide for the winding of material of various widths. First, the angle pieces 31 of the guide are adjusted by means of the nuts 33 in the slots 32 so that the space 34 105 conforms to the width of the material. Secondly, the train of gearing must be rearranged so that each step movement of the guide will be equal in length to the width of the ribbon and will occur at intervals corresponding with the rotation of the card. The calculation of the gears is a matter of mechanical skill already familiar in the art and need not be discussed in detail. All three gears 20, 20^e and 17 are interchangeable, but only 110 the intermediate gear need have its centre shifted in order that it shall reach the end gears. The provision for this adjustment is made in the several apertures 20^b formed in the web 20^a of the frame side 2 as shown 115 in Figure 8. The gears are loose for removal and tightened after renewal by means of the nuts already mentioned.

While a specific embodiment of the invention has been illustrated and described, it 125 is to be understood that various alterations in the details of construction may be made without departing from the spirit of the in-

vention as indicated by the appended claim.

Having thus fully described the invention, what I claim as new and desire to protect by Letters Patent is:

5 In a winding machine including a rotatably supported card holder, a guide arranged to traverse the said holder to wind a strip of material thereon, guide actuating means inoperatively associated therewith, gearing in-

terposed between the card holder and guide 10 actuating means, and a Geneva gear movement associated with the said gearing to intermittently operate the guide actuating means and the guide during the continuous rotary movement of the holder. 15

In witness whereof I have hereunto set my hand.

FREDERICK G. ROBINS.
